UNITED STATES PATENT OFFICE.

FRITZ ALDENDORFF, OF WILMERSDORF, BERLIN, GERMANY.

CONTROL-CIRCUITS FOR TELEPHONE SYSTEMS.

1,223,304.

Specification of Letters Patent. Patented Apr. 17, 1917.

Application filed March 16, 1914. Serial No. 825,103.

To all whom it may concern:

Be it known that I, FRITZ ALDENDORFF, a subject of the King of Great Britain, residing at 32 Mannheimerstrasse, Wilmersdorf, Berlin, Germany, have invented certain new and useful Improvements in Control-Circuits for Telephone Systems, of which the following is a specification.

My invention relates to circuits for controlling electromechanical switches in automatic or semi-automatic telephone systems and its object is to provide an improved form of two-wire system, or in other words an improved form of the kind of system in which only two conductors extend from the telephone stations or subscribers to the exchange and in which the switches in the exchange are controlled by the circuit loop formed of the two conductors without the aid of a third conductor such as an earth or common return conductor.

The invention consists in so arranging the circuits of the quick acting line relay of the circuit shifting or "change over" relay and of the release relay by which a calling subscriber controls the switch or switches through which a wanted connector is established, that the release relay and the "change over" relay (the relay which effects the "changing over" from the selecting action to the trunk-hunting or testing function in a selector or connector) are energized during the time in which the armature of the quick acting relay travels from its back to its front contact and vice versa. The release relay is only deenergized when the armature of the fast acting line control relay reaches its back contact and the deenergization of the change over relay only lasts while the armature of the fast acting relay touches its front contact. During the oscillations of the line relay armature caused by the selecting impulses set up by the switch controlling act of a subscriber or semi-automatic operation the moments during which the armature of the quick-acting relay touches its front and back contacts are so brief that the release and change over relays do not find time to allow their armatures to fall back. The release relay and change over relay are arranged to perform the releasing and change over function respectively when their armatures fall back. By a proper adjustment of the contacts of the line control relay the periods of deenergiza-

tion of the release and change over relay during the oscillations of the line relay armature can be made so brief that even ordinary relays may be depended on to hold their armatures steadily attracted during the oscillations of the line relay in the manner required of the release and change over relays. Special slow acting relays or relays responding to currents of different strengths as used in previously known two-wire systems may, therefore, be dispensed with in my system.

The release and change over relays in my system may be energized by opening paths of low resistance by which the said relays are ordinarily short-circuited. The opening of these short circuits is executed by a line control relay.

As the release and change over relays are energized by opening short circuits it is clear that the battery circuit supplying the current flowing through the short circuits must be closed before the line control relay commences to act. In order to prevent any waste of current while the system is not being used, the battery supply circuit for each set of switch controlling relays comprising a line control relay, a release relay and a change over relay is closed the moment the particular relay set is taken into use by a calling subscriber.

In the system proposed the combination of circumstances that produces the closure of the change over circuit consists in the energization of the line control relay and the simultaneous deenergization of the change over relay, the deenergization of the latter relay being caused by its being short-circuited when the former relay is energized. In a practical system it will happen that the line control relay will be connected to a calling subscriber (e. g. through a line finder or trunk finder) and energized for an appreciable time before the subscriber commences working his impulse transmitter. The combination of circumstances that produces the closure of the change-over circuit would thus be set up before the changing-over from the selecting action (e. g. stepping the wipers of a Strowger selector up to the required contact row) to the trunking action (e. g. rotary trunk hunting movement of the wipers of a Strowger selector) is necessary or permissible. I overcome this difficulty by providing a contact in the change over cir-

cuit which remains open until the selector has executed a movement in performing its selecting action.

The invention is illustrated in the accompanying drawing in which Figure 1 represents the circuits of a distributing switch or trunk finder which is individual to a subscriber and connects this subscriber, whenever he calls, to a trunk leading to a free selector or connector.

Fig. 2 shows the circuits of a connector. Any number of selectors may be inserted between the trunk finder and the connector in a well-known manner, these selectors being omitted as their representation is unnecessary for the clear comprehension of the invention.

In Fig. 1 S is a subscriber's station which is furnished with an impulse transmitter 20 I T and connected by wires a, b , through the contacts 1 2 of the test relay C R to the line relay L R of the trunk finder. O S₁ is an off-normal switch which is open only when the trunk finder is in its normal position and O S₂ is an off-normal switch the contacts 35, 40 of which are closed only in the normal position and the contact 34 of which is open only in the normal position.

In Fig. 2 C R is a line control relay which, whenever the connector is used, is switched in the circuit including the calling subscriber's loop, C R₁ is a change over relay, R R a release relay, S M a side switch or "circuit changer" magnet, S₁ S₂ are movable contacts controlled by the circuit changer magnet both contacts being shifted from one stationary contact to the next each time a current impulse is sent through the circuit changer magnet, L M is the lifting magnet of the connector which, to simplify the description, is assumed to be of the well-known up-and-around type, R M₂ is the rotary magnet, R M₁ the release magnet of the connector, T R₁ is a test relay, R R₁ a ringing current cut-off relay, R C R a ringing control relay and O S₃, O S₄ off-normal switches that are open only in the normal position of the connector. E R is an energizing relay which closes the energizing circuit of the change over and release relays C R₁ and R R at a suitable moment and only when the connector is taken into use. a_2, b_2, c_2 are wires which connect the subscriber S to the fixed contacts in the contact banks of the group of connectors through which the subscriber is accessible. w_4, w_5, w_6 are the wipers of the connector.

The manner in which the system operates will now be explained.

The subscriber S desiring a connection raises his receiver from its switchhook and connects the wires a, b in a well-known manner thus forming a loop through a, b through which current flows from the positive pole of exchange battery through L R,

2, b, S, a, 1, L R to the negative pole. The line relay L R then closes its contact 3 and the turning magnet R M (which acts upon the wipers w_1, w_2, w_3 in the well-known manner by a ratchet and pawl device) is alternatively energized and deenergized by current impulses flowing from the positive pole through interrupter I, R M, 3 to the negative pole. The turning magnet thus causes the wipers w_1, w_2, w_3 to brush past the fixed contacts connected to the trunks leading to the connectors, each trunk comprising three conductors a_1, b_1, c_1 . During the movement of the wipers the test relay T R, the circuit of which was closed at 4 by the energization of the line relay L R, tests the condition of the trunks and as soon as a free trunk is reached the test relay is excited by a current flowing from the negative pole through 4, T R, 5, w_3, c_1 , relays E R, 6 to the positive pole of the exchange battery. The relays T R and E R are energized. T R disconnects the line relay from the calling line by opening its contacts 1, 2 so that the line relay L R is deenergized and opens the turning magnet circuit at 3, which results in the wipers w_1, w_2, w_3 stopping on the free trunk. By the energization of the relay T R the calling subscriber's line a, b is extended through 8 and 9 to the wipers w_1, w_2 . Through the contact 10 a part of the winding of the test relay T R is short circuited which causes the potential on the test wire c_1 to be lowered and the trunk seized by the trunk finders to appear engaged to other trunk finders searching for a free trunk. At contact 11 the test relay T R closes a locking circuit for itself that is independent of the contact 4 which is now open. By connecting the negative pole of the battery through contacts 34, 11 and the winding of the test relay to the test wire c_2 coming from the connectors the calling line is made to appear engaged to all connectors through which connections to the calling line are attempted to be established as will be more fully explained later.

The moment the line relay L R was energized the negative pole of the battery was connected through the contact 4 and through T R to the test wire c_2 so that the calling line was made to appear engaged immediately the calling line commenced with the call, for as will appear more clearly later, a connection can only be made with a subscriber S when the positive potential predominates on his test wire c_2 .

When the relay E R was energized in the manner described above it closed the energizing circuit of the change over relay C R₁ and the release relay R R. The change over relay C R₁ is energized immediately by a current flowing from the positive pole through 7, 8, C R₁ to the negative pole.

But the winding of the relay R R is short circuited at first by the contact 8. A moment after the energization of E R and T R the line control relay C R receives current on account of the closure of contacts 5 8', 9 of relay T R, this current flowing from the positive pole through C R, a_1 , w_1 , 8', a , S, b_2 , w_2 , b_1 , C R, to the negative pole. The relay C R then opens the short circuit of the relay R R at 8 and closes a short circuit 10 about the change over relay C R₁ at 12, this relay being now deenergized while the release relay R R closes the stepping or measuring circuit of the connector at 16 and opens release circuit at 18. 15 The function of the change over relay C R₁ is to shift or change over the stepping or measuring circuit (positive pole, 7, 14, 16 S₁), which is controlled by the line control relay C R, from the lifting magnet to the rotary magnet and then to change over the connector from its rotary action to its testing action. As far as the invention is concerned the character of the actions taking 20 place before and after the change over function is of no importance as the invention has to do with the "change over" itself and the means for accomplishing the change over may be used for changing over from any 25 kind of action to any other kind of action. 30 The change over is accomplished at the end of each series of stepping or measuring impulses (by which the amount of movement of a switch or connector is determined) whenever the front contact 15 of the line 35 control relay is kept closed for an appreciable period of time. It will happen in the practical working of the system that when a calling subscriber is connected by his trunk 40 finder Fig. 1 to the next switch Fig. 2 the line control relay C R in this switch will be energized and its contact 15 closed for an appreciable time before the calling subscriber commences working his impulse 45 transmitter I T and sending in the selecting impulses. In order to prevent a change over by this first long closure of the contact 15 the change over circuit (positive pole, 7, 15, 17, O S₄, S M, negative pole) is kept open at 50 O S₄ until this contact O S₄ is closed which does not happen until the first selecting action of the switch or connector has commenced. Therefore, when the change over relay C R₁ is deenergized by the short circuit of appreciable duration at the contact 55 12 of the line control relay and the contact 17 is closed by this deenergization, the change over impulse, which would flow through 7, 15, O S₄ and through the change over magnet, is prevented by the contact O S₄ being open. 60 Upon the subscriber S now working his impulse transmitter I T he causes in a well-known manner a number of openings of his line loop a , b that corresponds to the number 65 of the wanted line and at each opening the line control relay C R lets its armature drop back so as to close the contact 14 and open the contact 12. The contacts 8 and 12 are so adjusted as to be hardly closed during the 70 oscillation of the armature of C R and so that if they are closed at all the closure will only take place when the armature is in its extreme rear or front position. The contact 14 is so adjusted as to be closed rather 75 early in the course of the travel of the armature of C R from its forward to its back position. The closures of contact 14 result in energizations of the lifting magnet L M by current impulses from the positive pole 80 through 7, 14, 16, S₁, L M to the negative pole of the battery, whereby the wipers w_4 , w_5 , w_6 are lifted to a contact row containing the wanted line. 85 On account of the above-described adjustment of the contacts 8 and 12 the short circuitings of the relays C R₁ and R R during the oscillations of the armature of the line control relay are so brief in duration that these relays do not find time to release 90 their armatures during the time the selecting impulses are being sent. Therefore the contact 16 will be kept closed and the contact 17 opened during this time. At the finish of the first series of selecting impulses the line 95 control relay C R will keep its armature attracted steadily for an appreciable time so that the contacts 15 and 12 will be kept closed. The latter contact will short circuit and deenergize the change over relay C R₁ 100 and then as soon as this relay allows its armature to fall back so as to close the contact 17 a change over current impulse will flow from the positive pole through 7, 15, 17, O S₄, which was closed the moment the wipers 105 w_4 , w_5 , w_6 were lifted, and through the circuit changer magnet S M to the negative pole of the battery. The circuit changer magnet then moves the movable contacts S₁, S₂ into their second positions onto the contacts 29 and 30. The shifting of S₁ to 29 changes the measuring circuit over from the lifting magnet L M to the rotary magnet R M₂ and upon the calling subscriber now 110 working his impulse transmitter I T a second time rotary impulses will flow from the positive pole through 7, 14, 16, S₁, R M₂ to the negative pole whereby the rotary magnet R M₂ is caused to turn the wipers w_4 , w_5 , w_6 around until they reach the set of bank contacts connected to the wanted line. 115 When the rotary selecting impulses cease the line control relay C R is again energized steadily and the contact 12 is closed for an appreciable time so that the contacts 17 and 125 15 are closed simultaneously and the circuit changer magnet S M is energized and moves the movable contacts S₁, S₂ into their third positions and closes the circuit of the test relay T R₁ through S₂ and 31. The circuits 120 130

belonging to the wanted subscriber are arranged at the trunk finder in the same way as those of the calling line. Therefore if the wanted line is busy through itself having originated a call its test relay T R at its trunk finder will be energized. By the shifting of contact 33 from 32 to 11 the lower end of the winding of the relay T R will be disconnected from the positive pole and connected to the negative battery pole through 34. The desired line will therefore be rendered engaged and the test relay T R₁ in the connector trying to establish a connection will not be energized because both ends of its winding will be connected to the negative pole of the battery (through S₂, 31, 21, and 34, 11, T R, c₂ respectively).

If the wanted line is free its test wire (similar to c₂) will be connected through its test relay (similar to T R Fig. 1) and through parts similar to 33, 32, O S₂, resistance 36 to the positive battery pole and therefore, when the circuit changer contact S₂, Fig. 2, shifts into its third position a current will flow from the negative pole through S₂, 31, 21, T R, 33, 32, O S₂, 36 to the positive battery pole. The relays T R₁ and T R will attract their armatures the latter disconnecting the line relay L R of the wanted subscriber from the wanted line and closing a new path from the positive pole through 35, 11 and the former connecting the ringing current source R M₃ to the wanted line through R C R, 27, 26 and short circuiting a part of its winding at 28, thereby immediately lowering the potential on the test wire c₂ of the wanted line and rendering it engaged *i. e.* making it impossible for other test relays T R₁ of other connectors to be energized on connecting to the same wanted line.

Ringing current will now flow from the ringing machine R M₃ through R C R, 27, 26, w₄, a₂, a, wanted subscriber's bell, b, b₂, w₅, 23, interrupter 37 to the other pole of the ringing machine R M₃. When the wanted subscriber responds to the call by raising his receiver from its switchhook the ringing current flowing through the ringing control relay is strengthened sufficiently to energize this relay causing it to close its contact 22 and to energize the ringing cut-off relay R R¹ by a current which flows from the positive pole through 22, R R¹ to the negative pole of the battery. The relay R R¹ closes its contacts 24, 25 and cuts off the ringing machine R M₃ by opening its contacts 23, 26. The relay R R¹ closes a locking circuit for itself through its armature 38, this locking circuit extending from the negative pole through R R¹, 38, O S₃ to the positive pole and being independent of the contact 22. The calling subscriber is now connected to the called subscriber through a, 8, w₁, a₁, c o₁, 25, w₄, a₂ and a of the called subscriber,

b₁, b₂ of this subscriber and through w₅, 24, c o₂, b₁, w₂, 9, b.

When the calling subscriber replaces his receiver and thus interrupts the connection between his line limbs a and b for an appreciable period the release relay R R is steadily short circuited by the contact 8 and allows its armature to drop back. The release circuit at the exchange is then closed at 18 and the release magnet is energized by a current which flows from the positive pole through O S₃, release magnet R M₁, 18 to the negative pole. The release magnet remains energized until the wipers w₄, w₅, w₆ return to their normal position when the off normal switch O S₃ is opened. While the wipers are returning to their normal position the release magnet keeps a contact 21 open and thereby prevents the test or busy potential being momentarily applied to the lines the bank contacts of which the wipers touch in returning to their normal position.

By opening a contact 20 the release magnet interrupts the circuit of the relays T R and E R. E R thereupon opens the circuit of C R, at contact 7 and T R closes the circuit of the turning magnet R M at 38 which extends from the positive pole through I, R M, 39, O S¹, 38 to the negative pole of the battery. The turning magnet R M then steps the wipers w₁, w₂, w₃ around until they reach their normal position in which the contact O S₁ is opened and breaks the turning magnet circuit.

While the wipers w₁, w₂, w₃ of the trunk finder are being moved into their normal positions the test circuit leading from the positive pole through 36, 40, 32, T R, c₂ is kept open at 40 in order to prevent the possibility of the relay T R being energized and the trunk finder stopped by a subscriber interrupting to make a connection to the partly released line through a connection Fig. 2. If the trunk a₁, b₁, c₁ upon which the partly released trunk finder were thus irregularly stopped just happened to be in use, this irregular stoppage of the trunk finder wipers would result in three or four parties being interconnected.

I claim:

1. In a switching system for interconnecting lines, a current source, a selector for selecting and testing said lines, a selecting relay for controlling the selecting function of said selector, an oscillatory armature on said selecting relay having back and front positions, and an electromagnet for initiating the testing function of said selector, said electromagnet being energized by said current source the moment the armature of the said selecting relay leaves its front position.

2. In a switching system for interconnecting lines, a current source, a selector for selecting and testing said lines, a selecting relay for controlling the selecting function of

said selector, an oscillatory armature on said selecting relay having back and front positions an electromagnet that is energized the moment the armature of the said selecting relay leaves its front position and a circuit for initiating the testing function of said selector, which circuit is rendered operative by the deenergizing of said electromagnet when the said oscillatory armature remains in its front position.

3. A switch with groups of contacts, selecting means for selecting a group of contacts, testing means for testing the contacts of said group, a switch control relay with an oscillating armature having two positions, and a change over relay which receives current during the travel of the armature of the control relay from its one position to its other position, the operation of the said testing means being initiated by the said change over relay.

4. In a switching system for interconnecting lines, a current source, a selector for selecting a line and for changing its electrical condition, a selecting relay for controlling the selecting operation of said selector, an oscillatory armature on said selecting relay having back and front positions and an electromagnet for controlling the operation of the said selector by which it changes the condition of a selected line, said electromagnet being energized by said current source in the period during which the armature of the said relay travels from its front position to its back position.

5. In a switching system for interconnecting lines, a current source, a switch for performing operations of different characters, a relay for causing the said switch to perform one operation, an electromagnet for causing the said switch to change from one operation to another operation, an oscillatory armature on said relay having back and front positions, said electromagnet being energized by said current source in the period during which the armature of the said relay travels from its front position to its back position.

6. In a switching system for interconnecting lines, a current source, a switch for performing operations of different characters, a relay for causing the said switch to perform one operation, a front contact on said relay, an electromagnet for causing said switch to change from one operation to another operation, a contact member for engaging with said front contact, an electrical connection between the one end of the winding of the said electromagnet and the said front contact and another electrical connection between the other end of the said winding and the said contact member.

7. In a switching system for interconnecting lines, a current source, a switch for selecting a line and for performing another

switching function, a selecting circuit for controlling the selecting operation of said switch, a change over circuit for changing the switch from its selecting operation to another switching function, a change over relay with a back contact for controlling the change over circuit, a selecting relay with front and back contacts, said selecting circuit being closed through a back contact of the selecting relay and the winding of the said change over relay being short circuited whenever the selecting relay closes its front contact.

8. In a switching system for interconnecting lines, a current source, a selector for selecting a line and for changing its electrical condition, a selecting relay for controlling the selecting operation of said selector, an oscillatory armature on said selecting relay having back and front positions, an electromagnet for controlling the operation of the said selector by which it changes the condition of a selected line, a circuit including the said current source, the said electromagnet and a normally open contact which is closed only whenever the said selector is taken for use, and a shunt of low resistance which deprives the electromagnet of current whenever the said armature is in its extreme front position.

9. In a switching system for interconnecting lines, a current source, a selector, a selecting relay for causing the said selector to select a wanted line, a change over electromagnet for causing the selector to change the electrical condition of a selected line, a restoring electromagnet for restoring the selector to its normal position, back and front armature contacts on the said selecting relay, a shunt of low resistance which is closed about the change over electromagnet when the said front armature contact is closed and a shunt of low resistance which is closed about the restoring electromagnet when the said back armature contact is closed.

10. In a switching system for interconnecting lines, a current source, a switch performing operations of different characters, a relay for causing the said switch to repeat a certain operation, an electromagnet for causing the said switch to change from one operation to another operation, a restoring circuit for restoring said switch to its normal position, an oscillatory armature on said relay having front and back positions, a shunt of low resistance which is closed about the said electromagnet when the said armature is in its front position and means for closing the said restoring circuit when the oscillatory armature remains in its back position.

11. In a switching system for interconnecting lines, a current source, a switch for performing operations of different characters, a controlling relay for controlling the

amount of an operation performed by the said switch, a primary circuit for enabling the switch to perform one operation a secondary circuit for enabling the switch to 5 perform another operation, a change over circuit for transferring the action of the said controlling relay from the primary circuit to the secondary circuit, a change over electromagnet in the change over circuit, a 10 front contact on the said controlling relay and a back contact on the change over electromagnet for closing the change over circuit, and an off-normal contact included in the change over circuit that is closed only 15 when the said switch is in an off-normal position.

12. A switch for performing a plurality of functions, a source of current, a switch control relay with an oscillating armature having two positions, and a change over 20 relay for causing the switch to change from the performance of one function to another function, said change over relay receiving current during the travel of the armature of the control relay from its one position 25 to its other position.

In witness whereof I have signed this specification in the presence of two witnesses.
FRITZ ALDENDORFF.
